N. O. HENAUT

MILLINER'S SHEARS

Filed May 29, 1924

UNITED STATES PATENT OFFICE.

NELLIE O. HENAUDET, OF BUTTE, MONTANA.

MILLINER'S SHEARS.

Application filed May 29, 1924. Serial No. 716,792.

To all whom it may concern:

Be it known that I, NELLIE O. HENAUDET, a citizen of the United States, residing at Butte, in the county of Silver Bow and State 5 of Montana, have invented certain new and useful Improvements in Milliners' Shears; and I do declare the following to be a full, clear, and exact description of the invention, such as will enable others skilled in the art 10 to which it appertains to make and use the same.

My invention relates to improvements in milliners' shears, such as those shown in my U. S. Patent Nos. 617,018 and 1,432,246. The 15 shears shown by each of these patents comprise briefly a pair of pivoted blades, a pair of handle-carrying shanks projecting rearwardly beyond the blade pivot, a pair of needle-gripping lugs carried by the handles, a 20 lateral enlargement on one of the shanks, and a forwardly projecting lug carried by this enlargement, the other shank being receivable between the last lug and the first-named shank when the handles are moved toward 25 each other. One object of the present invention is to improve upon shears of the general type above set forth, by providing the inner side of the last-mentioned lug with a cam which co-operates with the shank, 30 above identified as the "other shank", for the purpose of contracting tubular clasps which are used in making hat-frames, for the purpose of connecting the ends of certain stiff wires, used principally in reinforcing wide 35 hat brims. The cam and the "other shank" press oppositely against the clamp when the latter is inserted between them, and a further object of the invention is to provide co-acting cam surfaces on the handle-carried lugs, 40 which surfaces are operable to force one shank laterally with respect to the other, thus forcing the clasp-contracting lugs and the co-acting shank tightly toward each other during the contracting operation of the 45 clasp. These co-acting cam surfaces on the handle-carried lugs are also of great advantage in gripping needles to pull them through the work, to remove them from or apply them to a sewing machine, for grasping numerous 50 other articles used in the art of hat making, and for holding the points of the blades against each other when using such points.

With the foregoing objects in view, the invention resides in the distinct improvements 55 hereinafter fully pointed out and claimed,

and illustrated in the accompanying drawings.

Figure 1 is a perspective view showing the shears opened and a wire-connecting clasp about to be engaged with the cam of the clasp- 60 contracting lug;

Fig. 2 is a view similar to Fig. 1 but illustrating the clasp contracted by closing the shears;

Fig. 3 is a detail perspective view illustrating more particularly the formation of the cam at the inner side of the clasp-contracting lug; and

Fig. 4 is an end elevation showing more particularly the handle-carried lugs and 70 their co-acting cam surfaces.

In the drawing above briefly described, the numerals 1 and 1^a designate crossed blades pivoted together at 2 and provided with shanks 3 and 3^a projecting rearwardly 75 beyond the pivot, said shanks carrying handles 4 and 4^a. At 5 and 5^a wire receiving and bending grooves are shown, and at 6 and 6^a wire cutters have been illustrated. The shank 3 is provided with a lateral enlargement 7 in the inward path of the shank 3^a, and a lug 8 projects forwardly from said enlargement 7, said lug being spaced from the adjacent inner side of the shank 3 so that the shank 3^a is easily receivable between the 80 two. Short necks 10 and 10^a project rearwardly from the handles 4 and 4^a and are provided with co-operable lugs 11 and 11^a.

The general structure above described is substantially shown in the patents above referred to, but the lug 8 has been made much heavier to resist strain to which it is now subjected, and the formation of the lugs 11 and 11^a have been improved, as hereinafter set forth.

Formed in the inner side of the lug 8, is a transverse, preferably V-shaped groove 9 which opens through the upper edge of said lug and preferably decreases gradually in depth toward its lower end. This groove 100 constitutes a cam which is adapted to co-operate with the adjacent portion of the shank 3^a to contract a tubular clasp C, for connecting the ends of wires W. In performing this operation, the wire ends are inserted 105 into the clasp and this clasp is disposed between the lug 8 and the adjacent portion of the shank 3, as illustrated in Fig. 1, the clasp being then positioned in the groove 9. When the shears are now closed, a portion of 110

the shank 3^a co-operates with the cam 9 in exerting inward pressure on opposite sides of the clasp, thus effectively contracting the latter to bind it tightly upon the ends of the 5 wires.

For the purpose of forcing the shank 3^a toward the lug 8 and vice versa, when a clasp is being contracted, I form the lugs 11 and 11^a with oblique cam surfaces 12 and 10 12^a, shown more particularly in Fig. 4. These surfaces contact with each other before the shears have completed the contracting operation upon the clasp, but they 15 do not come into appreciable contact until after the blades 1 and 1^a have almost closed. Thus, while the cam surfaces in question will not interfere with proper operation 20 of the blades 1 and 1^a, they will force the shank 3 toward the right and the shank 3^a toward the left, thus exerting sufficient pressure 25 against the clasp C to insure its effective contraction. The surfaces 12 and 12^a are also co-operable with each other to hold the points of the blades against each 30 other when cutting with said points, and are useful for the purpose of grasping needles or any other articles, such as pieces of wire used in making hat frames. The angular relation of the surfaces in question, with 35 respect to the shears, is such that said surfaces may be very conveniently used for a number of purposes, one particular adaptation, being for the removal and insertion of sewing-machine needles.

35 It will be seen that I have distinctly improved upon shears of the type covered by my previous patents. Excellent results may be obtained from the construction shown and it is therefore preferably followed, but 40 within the scope of the invention as claimed, minor changes may be made.

I claim:

1. An improvement in milliners' shears having pivoted blades, handle-carrying 45 shanks extending rearwardly beyond the pivot of the blades, a lateral enlargement

on one shank in the inward path of the other shank, and a forwardly projecting lug on said enlargement between which and said one shank said other shank is receivable, 50 said improvement comprising a cam at the inner side of said lug to co-act with said other shank in contracting a tubular wire-connecting clasp.

2. A structure as specified in claim 1, said 55 cam being formed by a groove in the inner side of said lug, said groove opening through one edge of the lug and gradually decreasing in depth towards its other end.

3. An improvement in milliners' shears 60 having pivoted blades, handle-carrying shanks extending rearwardly beyond the pivot of the blades, a pair of co-operable lugs projecting rearwardly from the handles, a lateral enlargement on one shank 65 in the inward path of the other shank, and a third lug projecting forwardly from said enlargement in spaced relation with said one shank to permit reception of said other shank between the latter and said third lug; 70 said improvement comprising a cam at the inner side of said third lug to co-act with said other shank in contracting a tubular wire-connecting clasp, and a pair of oblique cam faces 75 on said co-operable lugs, said cam faces being co-active in forcing said second shank toward said third lug when a clasp is being contracted, and in grasping needles and other articles.

4. An improvement in shears having 80 crossed pivoted blades, handle-carrying shanks projecting rearwardly beyond the blade pivot, and co-operable lugs extending rearwardly from the handles; said improvement comprising co-acting cam surfaces 85 on said lugs active to laterally shift the blades and handles and hold the points of the former against each other.

In testimony whereof I have hereunto affixed my signature.

NELLIE O. HENAUT.
